Inventor,
Fred H. Burk, by
G. Kennedy,
Attorney.

UNITED STATES PATENT OFFICE.

FRED H. BURK, OF WATERLOO, IOWA.

CABINET FOLDING IRONING BOARD.

Application filed October 27, 1923. Serial No. 671,112.

To all whom it may concern:

Be it known that I, FRED H. BURK, a citizen of the United States of America, and a resident of Waterloo, Black Hawk County, 6 Iowa, have invented certain new and useful Improvements in Cabinet Folding Ironing Boards, of which the following is a specification.

My invention relates to improvements in 10 foldable ironing boards, and the object of my improvement is to supply a device of this class which is foldably mounted in a cabinet, the device being constructed for simplicity and strength, ease of operation, ar- 15 ranged so that when folded back into a cabinet it will be stably positioned therein, and whose movable bracing means is constructed to facilitate proper support of the ironing board when extended.

20 The above object I have accomplished by the means which are hereinafter described and claimed, and which are illustrated in the accompanying drawings, in which Fig. 1 is a front elevation of my improved device, 25 with the cabinet door opened, and the ironing board folded back thereinto, parts of the jambs being broken away. Fig. 2 is a vertical section from front to rear of said cabinet, on a larger scale, with the ironing board and its connections in side elevation, and the dotted lines showing the board ex- 30 tended. Fig. 3 is a detail view of the swing- 35 ing brace and slide roller for the ironing board. Fig. 4 is a rear end elevation of the ironing board, showing its pintle-carrying body secured thereon.

The cabinet for the ironing board 1 has an open front between side jambs 2, and is provided with a swinging or hinged door 4. 40 The jambs have parts within the cabinet provided with vertical grooves or slide- 45 ways 3.

The board 1 has a cylindrical bar 5 secured across the lower face thereof at its rear end by means of bolts 7 and nuts 16. A cylindrical pintle 6 of less diameter projects outwardly from the ends of the body 5 into sockets in the inner wall of the sides of the cabinet, to rock therein.

50 A cross-bar 10 is secured by screws 11 or nails upon the lower face of the board 1 a little to the rear of the middle thereof and has a medial longitudinal groove 13 along its face which contacts with the board to 55 receive the cross part 12 of swinging rod members 9. A cylindrical body 8 is orificed

near its opposite ends to receive the end parts of the members 9 therethrough, and secured by nuts 14 and 15 on opposite sides of the body 8. The end parts of the body 8 60 are seated slidably in the grooves 3, so that the upper and lower closed ends of the grooves limit the up and down movements of the body 8. When the ironing board is extended, the pintle ends of the body 8 are 65 at and held by the lower closed ends of the grooves 3, and when the board 1 has been swung back into the cabinet, the ends of said body 8 are positioned at the upper closed ends of said grooves 3. As the brace-mem- 70 bers 9 are integral with their connecting cross part 12, they provide strong bracketed supports for the horizontal board, capable of resisting much pressure while the latter is in use. 75

The cross-bar 10 provides a strong reinforcement for the board to prevent its warping or splitting.

It will be observed that the sockets for the board pintle 6 are positioned consider- 80 ably to the rear of and below the upper ends of the grooves 3. As shown in Fig. 1 in the full lines, when the ironing board 1 has been swung back into the cabinet, this mode of pivoting the board pintle 6 below and to the 85 rear of the ends of the body 8 when the latter are at the upper ends of the grooves 3 locates the board in a very stable raised position, a little inclined rearwardly, where its whole weight is to the rear of said pintle, and 90 where the board cannot be accidentally tilted forward except by the use of purpose- 95 ful force. As the weight of the brace-mem- bers 9—12 is supported on the board 1 to the rear of the pintle 6, this weight is added to 100 that necessary to be lifted to swing the board 1 forward.

Having described my invention, what I claim as new, and desire to secure by Letters Patent, is:

1. An apparatus of the class described, comprising an inclosure having a front opening and having sockets in its opposite sides spaced a considerable distance from its back wall, an ironing board having a pintle rock- 105 ably mounted in said sockets, said inclosure having upwardly directed closed end guideways at its opposite sides positioned forward of said sockets, and a brace element swing- 110 ingly connected to said ironing board and having a pintle movable to and fro in said guideways, the brace pintle engaging the

lower ends of said guideways when the ironing board is extended, and engaging the upper ends of the guideways when the board is tilted backwardly.

5 2. An apparatus of the class described, comprising an inclosure having a front opening and having bearing sockets in its opposite sides, an ironing board having a pintle fixed upon the under side of its rear end and 10 rockably mounted in said sockets, said inclosure having vertical guideways at its opposite sides positioned forward of said sockets, said sockets being located approximately 15 medially to the rear of said guideways, and a brace-rod whose middle part is pivotally mounted across the middle of the lower face

of said ironing board and bent at each side edge of said board to have two members extending in the same direction, a cross-body fixed on the ends of said members and having outwardly projecting ends which are mounted to slide to and fro in said guideways, so that when they are positioned at the lower ends of the guideways the ironing board is held in an extended position, and 20 when they are positioned at the upper ends of the guideways the ironing board is tilted back into said inclosure to the rear of said pintle.

Signed at Waterloo, Iowa, this 25th day 25 of Sept., 1923.

FRED H. BURK.
